(57) **CLAIM**

The ornamental design for an interior panel for a vehicle, as shown and described.

DESCRIPTION

FIG. 1 is a top front left perspective view of an interior panel for a vehicle according to the present invention.

FIG. 2 is a front left perspective view thereof.

FIG. 3 is a top rear right perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof; and,

FIG. 10 is a bottom view thereof.

In the drawings, the broken lines depict portions of the interior panel for a vehicle the form no part of the claimed design.
